CLAIM

The ornamental design for a mobile device with graphical user interface for shooting, modeling, and editing of scenes, as shown and described.

DESCRIPTION

FIG. 1 is a front view of a first image in a sequence of a mobile device with graphical user interface for shooting, modeling, and editing of scenes, showing the new design in a non-claimed environment;

FIG. 2 is a front view of a second image thereof;

FIG. 3 is a front view of a third image thereof;

FIG. 4 is a front view of a fourth image thereof; and,

FIG. 5 is a front view of a fifth image thereof.

The appearance of the animated image sequentially transitions between the images shown in FIGS. 1-5. The process or period in which one image transitions to another forms no part of the claimed design.

The outermost broken lines illustrate a mobile device, which is the environment of the design, and forms no part of the claim. The innermost broken line rectangle illustrates a display screen and forms no part of the claimed design.

1 Claim, 5 Drawing Sheets
